UNITED STATES PATENT OFFICE.

FRED PFISTNER OF JERSEY CITY, NEW JERSEY.

BUILDING-CORNER GUARD.

Application filed February 17, 1927. Serial No. 168,868.

The main object of this invention is to provide a guard which is mounted at the corners of any type of frame building for the purpose of forming a leak-proof fit so that no seepage of water is possible at the corners. The corner guard is composed of a metal deformed member which extends the length of the corners against which the end portions of shingles, of wood asbestos 10 or strip, and also clap, novelty, and colonial boards abut. Special features add to the adaptability of the corner guard and comprise securing extensions which are fluted to serve as a drain for any moisture which may 15 trickle beneath the boards and a filler which prevents a bend provided with the guard from being collapsed by an inadvertant pressure.

The above and other objects will become 20 apparent in the description below in which characters of reference refer to like-named parts in the drawing.

Referring briefly to the drawing, Figure 1 is a perspective view showing the application 25 of the corner guard to the corner of a house which is covered on one side by shingles and on the other side by clap boards.

Figure 2 is a top plan view of the corner 30 guard as mounted on the corner of a building.

Figure 3 is an elevational view as seen from one side of Figure 2.

Figure 4 is an elevational view as seen 35 from another side of Figure 2.

Referring in detail to the drawing, the numeral 10 indicates the usual upright member which is used as part of the building construction in frame houses. The member 40 illustrated forms a corner support and at its outer two sides has facing boards 11 and 12 secured thereto by nails or similar other means which are not shown on the drawing. The intersection of the two boards 11 and 12 45 forms an external corner which is adapted to be covered by the corner guard shown in the several views of the drawing.

The corner guard consists of a rectangular strip of copper or other suitable material 50 which at a position intermediate its width is formed into a quarter round bend consisting of a curved face 13 from the ends of which ears 14 and 15 extend at right angles to each other. These ears at the point of 55 intersection continue as parallel positioned

spacers 16 which extend to the corner of the building at a diagonal thereto. The outer extremities of the spacers again continue therefrom as relatively wide legs 17 and 18 which lie at a 45 degree plane to the 60 surface of the spacers and lie flush on the surface of the boards 11 and 12 at the intersection thereof. The surface of the legs intermediate their width is provided with undulating curved corrugations 19 which 65 form channels or runways 20 for the water or moisture which may collect on the surface of the legs. At any convenient positions on the legs of the corner guard the same may be pierced by nails 22 and the 70 latter are secured in the material of the boards 11 or 12.

The guard is adapted to be mounted at the corners of buildings and the bend, the ears and the spacers are reduced at one end, 75 as shown by the numeral 21, so that the full-sized end of an adjacent length of corner guard may be slipped over the reduced end when joining both sections or lengths together. The legs 17 and 18 provided with 80 the corrugations are entirely concealed from view beneath the shingles 23 or whatever other material is used to surface the building, the usual material being wood, asbestos 85 or strip shingles or clap, novelty or colonial boards. The bend provided at the intersection of the legs eliminates the necessity of mitering the material with which the building is faced and besides protects the construction in a leak-proof manner and is 90 quite ornamental in appearance. Should seepage occur at the corners during a heavy rain, which is sometimes likely, such seepage is carried off after being guided into the channels 20 of the corrugations.

It is to be noted that certain changes in form and construction may be made without departing from the spirit and scope of the invention.

I claim;

1. A corner guard comprising a pair of separated legs extending at right angles to each other, said legs being vertically corrugated, spacers extending from the legs where the legs meet, said spacers extending 105 at a diagonal to the corner described by the legs, a quarter round bend having a curved face extending from said spacers, and a filler in said bend for reenforcing the same.

2. A corner guard comprising a pair of 110

separated legs extending at right angles to each other, said legs being corrugated, spacers extending from the legs where the legs meet, said spacers extending at a diagonal to the corner described by the legs, a quarter round bend having a curved face and intersecting ears forming side walls exten-

tending from said face, a filler in said bend, and a reduced end at one end of each length of corner guard for telescoping one length of corner guard into the end of an adjacent length.

In testimony whereof I affix my signature.
FRED PFISTNER.
